CLAIM

We claim the ornamental design for a toilet, as shown and described.

DESCRIPTION

FIG. 1 is a top, front, right side, perspective view of a toilet showing our new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a top, front, right side, perspective view thereof;

FIG. 9 is a right side view thereof;

FIG. 10 is a left side view thereof;

FIG. 11 is a front view thereof;

FIG. 12 is a rear view thereof;

FIG. 13 is a top view thereof; and,

FIG. 14 is a bottom view thereof.

Broken lines of the disclosure represent portions of the toilet that form no part of the claimed design. The dash dot broken lines showing the boundary of the claim form no part of the claimed design.

1 Claim, 12 Drawing Sheets
